UNITED STATES PATENT OFFICE.

SIGMUND HORN AND MAXIMILIAN ZIPKES, OF NEW YORK, N. Y.

AEROPLANE.

Application filed August 8, 1927. Serial No. 211,350.

Our invention relates to aeroplanes and more particularly to a safety device which will serve to protect the aeroplane against what is generally known as nose dive, although the invention is useful for other purposes. The present device includes the ordinary parts of an aeroplane such as the wings or planes, fuselage, motor and steering apparatus, and the present invention is applied 10 as an additional feature to the aeroplane. While the invention is applicable to either a monoplane or biplane, we have shown it in the drawings as applied to an ordinary type of biplane. The invention consists in applying to the plane or wing of the aeroplane, preferably the upper one if it is a biplane, a sheet of material, preferably in the nature of a textile fabric which may be folded down flat against the surface of the plane, or be 15 lifted up or separated from the plane to form a pocket through which the air rushes between the plane and the fabric. Suitable means is provided, convenient to the flier, for placing the fabric referred to either in 20 what may be called the open or the closed position. When the fabric is in what might be called the closed position, it lies close to or flat to the open surface of the plane and performs no function, so that the aeroplane 25 is then operated as if the device were not present. When the device is in the open position it co-operates with the plane or one of the planes to form a pocket through which the air rushes, the pocket being open at the 30 front and back; and in the preferred construction the pocket decreases in width from the front towards the back; and further, in the preferred form the depth of the pocket between the plane and the top of the fabric decreases from the forward portion towards the 35 rearward portion. When the device is in the open or operative position the fabric forms an additional sustaining surface, and by reason of the shape of the pocket the air rushing 40 through it will prevent the aeroplane from making a nose dive at such an angle and speed as will cause the destruction of the aeroplane and injury to the operator. In the event the aviator meets with difficulties during flying, 45 for instance, if the motor should stall, there is a tendency for the aeroplane to go into a nose dive with disastrous results. With the

present device, however, even though the motor should stall the aviator may place the present device into open or operative position, 55 and the device will prevent a dangerous nose dive while the aviator is making a landing.

The device is also useful when taking off the ground because it increases the total lifting area beyond the point for which the usual 60 wing or plane surface is designed. Due to the folding or collapsing character of the device, it may be put into use at any time where conditions make it desirable, or it may be folded into inoperative position, allowing the 65 plane to function as if the device were not present, so that at all times the device is within the control of the aviator. Other advantages will be apparent from the following detailed description of our invention. 70

In the drawings forming part of this application,

Figure 1 is a perspective view of an aeroplane to which our invention is applied,

Figure 2 is a perspective view of a section 75 of one of the frame members which is attached to the wing of the aeroplane,

Figure 3 is a plan view of one of the wings of the aeroplane, showing the device applied thereto.

Figure 4 is a sectional view taken on the line 4—4 of Figure 3,

Figure 5 is a perspective view of the fabric, forming part of the device, and

Figure 6 is a perspective view of a portion 85 of the frame which is applied to the top of the aeroplane.

In the drawings we have shown an ordinary type of biplane, although as stated above our invention is not limited in its application to a biplane, as it may be equally well applied to a monoplane. Where applied to a biplane, the device is preferably attached to the upper or top plane in preference to the lower plane. 90

In the drawings we have shown the biplane composed of the lower plane 2 and an upper plane 3, connected by any type of struts or framework 4. In addition there is shown a fuselage 5 in the forward end of which is the 100 driving propeller 6 and on the rear are the elevating rudders 7 and the lateral rudder 8. As far as these portions of the aeroplane are concerned, they may conform to present

practice and are subject to all of the modifications of the present types of aeroplanes. As stated above, our invention is preferably applied to the upper plane 3. We have shown 5 bars 9, 10 which are preferably of triangular cross section, attached along the upper surface of the plane 3, and arranged adjacent the opposite ends of this plane. These bars are shown two in number and arranged so that they are separated a greater distance near the forward edge of the plane 3 and converge toward the rear edge of the plane, so that at their rear ends they are closer than at their forward ends. Preferably they extend beyond, or project from the rear end of the plane 3. These bars, in addition to their converging relation, are preferably arched to conform to the arched upper surface of the plane 3, to which surface they closely adhere. 10 15 20 The remaining portions of the frame of the present device consist of rods 11, connected each at one end with the forward end of one of the bars 9, 10, and these rods extend upwardly over the forward edge of the plane 3 and converge at a point over the middle line of this plane and are connected by a suitable coupling 12 with each other. There is a third rod 13 connected at its rear end with a cross member 14 which latter is contiguous with 25 30 35 and connected between the bars 9, 10. The rod 13 extends upwardly and forwardly in inclined relation to the plane 3 and it is connected at its forward end with the coupling 12 which unites the ends of the bars 11. 40 45 50 55 The flexible sheet 15 may consist of fabric or other pliable material and is shaped somewhat in accordance with the contour of the frame of the present device. This sheet is shown as having apertures 16 along two of its side edges and there is a lacing 17 passing alternately through these apertures in the sheet and the apertures 18 in the bars 9, 10 so that the side edges of this sheet are connected by the lacing with these side bars. We prefer to make this lacing of rubber or other elastic material which will be extended to some extent by the pressure of the air under the sheet 15 when it is in operative position and which lacing will tend to draw out the sheet to lie close to the top of the plane 3 when the device is out of operative position. In other words, with the lacing of elastic material the side edges of the sheet 15 may draw inwardly or away from the bars 9, 10 under the action of the wind pressure on the sheet 15 when in operation.

There is a guiding rope or cable 19 connected with the coupling member 12 at the meeting point of the several bars 11, 13, and this extends downwardly past the forward edge of the plane 3 and its lower end is connected with a member 20 which is attached to the forward portion of the fuselage. This cord or cable acts as a guide for the forward edge of the sheet 15. The forward portion of the

sheet is shown as having diverging edges 21 terminating in the forward point 22 at the middle of the sheet, and at this point the sheet is provided with a pulley 23 which is guided on the guiding rope 19. There is a pulley 24 attached to the coupling member 12, this pulley having two grooves for guiding the rope 25. The ends of this rope hang down in position to be grasped by the aviator in the fuselage and we have shown handles 26 on the opposite ends of this rope. The rope is formed in two runs, each extending first vertically upwardly from the handles 26, thence over the pulley 24, and thence outwardly and downwardly, then loop through the pulley 27 on the forward end of the fuselage. One run of this rope between the pulleys 24, 27 is attached to the bracket 28 which carries the pulley 23 on the forward edge of the fabric.

Operation.

When the device is not in operation it will lie in the position shown in Figure 1, in which case the sheet 15 will be held lowered at its forward end, the aviator having pulled on one of the handles 26 to draw the pulley 23 downwardly along the guiding rope 19 until the forward edge of the sheet projects over and hugs the forward edge of the plane 3. The tension of the lacing members 17 causes the remainder of the sheet to hug closely to the upper surface of the plane 3. In this condition the device performs no function and the aeroplane may be flown as if the device were not present.

Any time it is desired to place the device into operation the aviator draws on one of the handles 26 whichever one is necessary to move the pulley 23 upwardly toward the top of the frame, that is, toward the coupling member 12. This action lifts the leading edge of the sheet 15 at the center upwardly, so that the center portion of the sheet is spaced some distance from the top surface of the plane 3; and by reason of the shape of the sheet the top central line will converge toward the surface of the plane 3 from the forward end toward the rearward end of the sheet. The elasticity of the lacing members 17 allows the central portion of the sheet to be lifted in the manner described, the sides of the sheet being drawn somewhat inwardly in this operation. When the central portion of the sheet has been lifted in the manner described, then, due to the forward motion of the plane, air will rush in through the space between the top surface of the plane 3 and the under surface of the sheet 15 entering this space at the forward edge of the sheet and plane and passing out at the rear edges thereof. If the space between the plane 3 and the sheet 15 is converging, as shown in the drawing, the angle of incidence with which the air acts upon the sheet 15 will be 110

different to the angle of incidence upon the plane 3. If by reason of the angle of the aeroplane there is no resistance to its downward flight by the air on the plane 3, there will be at least some resistance to the same because the angle of incidence of the sheet 15 is different from that of the plane 3. If, therefore, the plane has a tendency to make a nose dive by reason of the motor having stalled, or for any other reason, the aeroplane will not get out of control or make such a rapid nose dive as to force it downwardly at a dangerous rate. If the space through which the air passes between the plane 3 and the sheet 15 decreases, as shown in the drawing, there will be sufficient increase in head resistance which will also serve to prevent a dangerous nose dive. Therefore, in making a landing the aviator may place the sheet 15 into operative position in the manner described, in order to prevent a dangerous nose dive, and possibly turning over of the plane. On the other hand, at the time of taking off from the ground, the sheet may be put into operative position in order to temporarily increase the lifting surface by adding the effect of the lifting surface of the sheet 15 to that of the plane, or planes, so that the aeroplane may take off after a shorter ground run than if the present device were not employed; and when the plane has reached any desired elevation the sheet may be placed in the inoperative position by pulling the necessary handle 26. This latter operation will cause the pulley 23 to be drawn down by the rope 25 along the guiding rope 19 until the forward edge of the sheet 15 is slightly below the front edge of the plane 3 and until the sheet lies close against the upper surface of this plane. It will be apparent, therefore, that the sheet 15 may be placed into operative or inoperative position at the will of the aviator to meet various conditions, either in flying, landing or taking off.

The present device is simple, inexpensive, and it may be made comparatively light in weight in order not to add greatly to the total weight of the aeroplane.

Having described our invention, what we claim is:

1. In an aeroplane the combination of a plane and a pliable member adapted to be folded closely against the top surface of said plane, or to be extended in position to form an air passage between the top of said plane and said member, said pliable member when in folded position having a central portion adapted to project forwardly and downwardly over the leading edge of said plane.

2. In an aeroplane the combination of a plane and a sheet adapted to be folded closely against the top surface of said plane, or to be extended in position to form an air passage between the top of said plane and said sheet, elastic means for drawing on the opposite

ends of said sheet substantially laterally of said plane, and means acting on the sheet intermediate the ends thereof for raising and lowering it in relation to the plane.

3. In an aeroplane the combination of a plane, bars extending across the upper surface of said plane, front to rear thereof, adjacent the opposite ends of said plane, a flexible sheet having its opposite edges engaged with said bars, and means for raising and lowering the central portion of said sheet to place it either in close relation to the top surface of said plane, or to extend it in position where the air will act on said sheet for the purpose set forth.

4. In an aeroplane the combination of a plane, bars extending across the upper surface of said plane, front to rear thereof, and diverging in relation to each other, and adjacent the opposite ends of said plane, a flexible sheet having its opposite edges engaged with said bars, and means for raising and lowering the central portion of said sheet to place it either in close relation to the top surface of said plane, or to extend it in position where the air will act on said sheet for the purpose set forth.

5. In an aeroplane the combination of a plane, an angular frame extending upwardly from the top surface of said plane with its highest portion located midway of the width of said plane, a flexible sheet having means for holding the side edges thereof adjacent said plane, and means associated with said frame for raising and lowering the central portion of said sheet.

6. In an aeroplane the combination of a plane, a frame including bars adjacent the forward edge of said plane, arranged to converge upwardly from the plane to a point midway of the length of said plane, a sheet and means for engaging the side edges thereof, a guiding member extending from the higher central portion of said frame downwardly and forwardly and connected to the fuselage, means on the central forward edge of said sheet co-operating with said guiding member, and means for raising and lowering the middle portion of said sheet for the purpose set forth.

7. In an aeroplane the combination of a plane having attaching means on the upper surface thereof, a sheet on the upper side of said plane, a lacing of elastic means for connecting said attaching members and the side edges of said sheet and means for elevating and lowering the middle portion of said sheet for the purpose of creating an air passage between the top of said plane and said sheet, or for placing said sheet in collapsed position upon said plane.

8. In an aeroplane the combination of a plane and a pliable member adapted to be folded closely against the top surface of said plane or to be extended in position to form

an air passage between the top of said plane and said member and means for holding said member in extended position whereby an air passage is formed between said plane and said member extending entirely lengthwise between said plane and said member, said air space being of decreasing vertical extent with

the lower portion towards the rear of said plane.

Signed at the city, county and State of New ¹⁰ York, the 28th day of June, 1927.
